UNITED STATES PATENT OFFICE.

CHARLES D. SAXTON, OF KALAMAZOO, MICHIGAN.

WATER PUMPING AND HEATING APPARATUS.

1,249,512.

Specification of Letters Patent. Patented Dec. 11, 1917.

Application filed March 21, 1916, Serial No. 85,606. Renewed October 29, 1917. Serial No. 199,212.

To all whom it may concern:

Be it known that I, CHARLES D. SAXTON, a citizen of the United States, residing at the city and county of Kalamazoo, State of Michigan, have invented certain new and useful Improvements in Water Pumping and Heating Apparatus, of which the following is a specification.

This invention relates to improvements in water pumping and heating apparatus.

The main objects of this invention are:

First, to provide an improved combined water pumping and heating apparatus.

Second, to provide an improved combined water heating and pumping apparatus which is automatic in its operation.

Further objects, and objects relating to structural details, will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Figure I is an elevation of a structure embodying the features of my invention, parts being broken away to better disclose structural details, various parts being shown in conventional form.

Fig. II is a detail section through the 35 steam delivery valve.

Fig. III is a detail longitudinal section through the ejector.

In the drawing, similar reference numerals refer to similar parts throughout the 40 several views.

Referring to the drawing, the steam generating boiler illustrated is provided with a plurality of coiled heating tubes 1 disposed within the casing 2 to be heated by the burners 3. The casing 2 is provided with a discharge flue 4 having a damper 5 therein.

Water is automatically delivered to the steam generating boiler through the supply 50 pipe 6 which is preferably provided with a back pressure drum 7 adjacent the boiler. This water supply pipe is, in practice, preferably connected to the water system of the city or other source of supply under pres-

sure. Gas is supplied to the burners 3 55 through the pipe 8 controlled by the valve 9.

The pilot burner 10 is connected by the pipe 11 to the gas supply pipe 8 in front of the valve 9. The pilot has a regulating valve 12.

13 represents the delivery pipe or system, such as the piping of a house, and is provided with one or more draw-off cocks 14.

15 is the water supply pipe which, in practice, leads to a cistern or other source 65 of supply from which the water is to be drawn. The pipe is provided with a check valve 15'. The pipe 15 is connected to the body member 16 of an ejector, the nozzle 17 of which is arranged to deliver to the venturi 19, as shown in Fig. III.

13 represents the delivery pipe or system, such as the piping of a house, and is provided with one or more draw-off cocks 14.

15 is the water supply pipe which, in practice, leads to a cistern or other source 65 of supply from which the water is to be drawn. The pipe is provided with a check valve 15'. The pipe 15 is connected to the body member 16 of an ejector, the nozzle 17 of which is arranged to deliver to the venturi 19, as shown in Fig. III.

The steam delivery pipe 20 is connected to the nozzle 17 of the ejector. The action of an ejector is well known and therefore is not enlarged upon herein. The delivery 75 pipe 20 of the boiler is preferably provided with a valve 21 arranged within the casing 22 and provided with a stem 23 with which the arm 24 on the rock shaft 25 engages.

This rock shaft is connected by the link 27 80 to the thermostat actuated lever or member 28, the thermostat being disposed in the section 20' of the generator delivery pipe between the valve 21 and the boiler. The details of the thermostat are not illustrated 85 as suitable thermostats are known in the art and the structural details of the thermostat form no part of my present invention.

The fuel valve 9 is controlled by pressure actuated means subject to the pressure 90 of the fluid in the delivery pipe 13. In the structure illustrated this actuating means comprises the casing 29 having a diaphragm 30 therein. One side of the casing is connected to the delivery pipe 13 by 95 the pipe 31. The diaphragm is provided with a stem 32 projecting through the other side of the casing 29 and operatively connected to a lever 33 mounted at 34.

A spring 35 is connected to the bracket 100 36 on the pipe 20 and acts on the diaphragm against the pressure within the casing.

A bar 37 is connected to the lever 33 and slidably supported by the bracket 36 and a second similar bracket 38. This bar is 105 notched at 39 to engage the arm 40 on the stem of the valve 9 so that the valve is opened and closed by this pressure actuated

member. A spring 41 holds the arm 40 in position to be engaged by the bar. The bar 37 is provided with an extension 42 connected to the arm 43 on the spindle 44 of the damper 5 so that the damper is automatically opened and closed when the gas is turned off and on. This is of advantage in that it prevents circulation of air through the boiler casing when the burners are cut off thereby preventing undue cooling of the generator.

With the parts thus arranged, the operation of the device is entirely automatic so that when the draw off cock 14 is opened water flows therefrom reducing the pressure in the system so that the pressure actuated member operates to turn on the gas to the heating burners. This generates steam in the boiler or generator which, upon reaching a predetermined degree of temperature, causes the thermostat to open the valve 21 in the generator discharge pipe so that the steam passes to the ejector and into the delivery pipe. The steam passing through the ejector not only draws the water through the supply pipe carrying it into the delivery pipe, but also heats the water so that I secure by this arrangement of parts a combined pump and water heating apparatus. When the draw off cock is closed pressure on the delivery pipe rises until the gas valve is closed through the pressure actuated mechanism. The extent to which the cock 14 is opened determines the temperature of the water. The capacity of the several pipes is preferably such that if the cock be fully opened cold water may be drawn through the same system or delivery pipe.

Parts of the apparatus are shown in the accompanying drawing mainly in conventional form as my present invention does not relate to the structural details thereof and suitable mechanisms are known.

My improved pumping and water heating apparatus is, as stated, entirely automatic and is not likely to get out of repair in use.

Having thus described my invention, what I claim as new and desire to secure by Letters Patent, is:

1. In a structure of the class described, the combination with a steam generating boiler including a casing provided with a discharge flue, a damper for said flue, a connection for delivering water under pressure to said boiler, said connection having a back pressure drum adjacent said boiler, a discharge pipe for said boiler, a valve for said boiler discharge pipe, a thermostat disposed in said discharge pipe in front of said valve and operatively connected thereto so that the valve is opened by said thermostat when the steam within the boiler discharge pipe reaches a predetermined temperature, a delivery pipe provided with a

draw-off cock, an ejector disposed between said delivery pipe and said boiler discharge pipe, a water supply pipe connected to said ejector, said supply pipe being provided with a return check valve, a pressure actuated member operatively connected to said delivery pipe, a fuel supply valve, a heating burner for said boiler, and operating connections for said pressure actuated member to said gas supply valve and damper. 75

2. In a structure of the class described, the combination with a steam generating boiler including a casing provided with a discharge flue, a damper for said flue, a connection for delivering water under pressure to said boiler, said connection having a back pressure drum adjacent said boiler, a discharge pipe for said boiler, a delivery pipe provided with a draw-off cock, an ejector disposed between said delivery pipe and said boiler discharge pipe, a water supply pipe connected to said ejector, a pressure actuated member operatively connected to said delivery pipe, a fuel supply valve, a heating burner for said boiler, and operating connections for said pressure actuated member to said gas supply valve and damper. 80 85

3. In a structure of the class described, the combination with a steam generating boiler, a flue for said generator, a damper for said flue, a connection for delivering water under pressure to said boiler, a discharge pipe for said boiler, a valve for said boiler discharge pipe, a thermostat disposed in said discharge pipe in front of said valve and operatively connected thereto so that the valve is opened by said thermostat when the steam within the boiler discharge pipe reaches a predetermined temperature, a delivery pipe provided with a draw-off cock, an ejector disposed between said delivery pipe and said boiler discharge pipe, a water supply pipe connected to said ejector, a pressure actuated member operatively connected to said delivery pipe, a heating burner for said boiler, a fuel supply valve, and operating connections for said pressure actuated member to said gas supply valve. 95 100 105

4. In a structure of the class described, the combination with a steam generating boiler, a flue for said generator, a damper for said flue, a connection for delivering water under pressure to said boiler, a discharge pipe for said boiler, a delivery pipe provided with a draw-off cock, an ejector disposed between said delivery pipe and said boiler discharge pipe, a water supply pipe connected to said ejector, a pressure actuated member operatively connected to said delivery pipe, a fuel supply valve, operating connections for said pressure actuated member to said gas supply valve and for said pressure actuated member to said damper. 110 115 120 125 130

5. In a structure of the class described, the combination of a steam generator, a heating means therefor provided with a fuel valve, a water supply connection, a delivery pipe provided with a draw off cock, an ejector connected to said boiler and operatively associated with said water supply and delivery pipe, means for operating said fuel valve actuated by the pressure of the fluid in said delivery pipe, a steam valve interposed between said ejector and steam generator, and a thermostat subject to the generator and operatively connected to said steam valve.
10. 6. In a structure of the class described, the combination of a steam generator, a delivery pipe, a water supply pipe, an ejector connected to said steam generator and operatively associated with said water supply and delivery pipes, means for controlling said steam generator actuated by the pressure of the fluid within said delivery pipe,
15. 7. In a combined water pumping and heating apparatus, the combination of a steam generator, a delivery pipe, a water supply pipe, an ejector connected to said steam generator and operatively connected with said water supply and delivery pipes, a generator controlling means comprising a pressure actuated member connected to said delivery pipe at the rear of the ejector, and means for controlling the delivery of steam to said ejector comprising a thermostat subject to said generator.
20. In witness whereof, I have hereunto set my hand and seal in the presence of two witnesses.
